UNITED STATES PATENT OFFICE.

JOHN B. SOUSA, OF RENO, NEVADA.

GAME.

Application filed April 21, 1926. Serial No. 103,536.

The object of this invention is the instruction and entertainment of children and provides a game which may be indulged in by others to advantage for passing idle moments in a pleasurable way.

The game consists of a base, preferably a board comprising hinged sections, a race course delineated thereon and comprising a plurality of tracks merging at opposite ends 10 or points into a single track, game pieces representing the racers, play indicators, such as dice, and scoring means.

While the drawings illustrate a preferred embodiment of the invention it is to be understood that in adapting the means to meet specific needs and requirements, the design may be varied and such other changes in the minor details of construction may be resorted to within the scope of the invention 20 as claimed, without departing from the spirit thereof.

For a full understanding of the invention and the merits thereof, reference is to be had to the following description and the 25 drawings hereto attached, in which,—

Figure 1 is a perspective view of a game board embodying the invention,

Figure 2 is a detail view of one type of game pieces,

Figure 3 is a detail view of the score pegs, Figure 4 is a detail perspective view of the play indicators, and

Figure 5 is a perspective view of one of the play indicators.

Corresponding and like parts are referred to in the following description and designated in the several views of the drawings by like reference characters.

The game board comprises a base 1, which 40 may be of any construction and size. In the preferable form the game board 1 comprises similar sections which are hingedly connected so as to fold one upon the other. One of the sections has recesses formed 45 therein to provide pockets 2 and 3 for receiving the game pieces, score pegs and play indicators. A race course 4 is delineated upon the play surface of the board and is of elliptical outline. The race course 4 contains a plurality of tracks 5 which merge 50 into a single track 6 at opposite ends or points of the course. Each of the tracks is outlined by openings of a size to receive the pins 7 of game pieces 8. The single tracks 5 occur in line with the major axis of the race course. The starting line 9 is prefer-

ably in line with the minor axis of the race course and at one side thereof.

The game pieces 8 may be of any form depending upon the nature of the race and 60 when the game partakes of the nature of a derby the game pieces 8 will have the outline of a horse, but for a marathon the game pieces will present the outline of a human being. In this connection it is observed that 65 the game pieces may have any form according to the nature of the race. The game pieces will be of contrasting color and each will bear a number and are entered in numerical order.

The play indicators consist of dice 10, 70 three being usually provided. Two of the dice will bear, upon their respective sides, the characters 0 to 5, both inclusive, and the third dice will bear the letter B, the characters, 0 and 6, and the designations —, + and ×. The play indicators may be cast in any of the usual ways of throwing dice and when the upper sides of the three dice present numbers the sum of such numbers indicates the number of openings of the game piece of the player to be advanced along the track. However, should one of the dice present the letter B upon the upper side the 75 sum of the numbers appearing on the other two dice represent the number of openings of the game piece to be moved backward. In the event of an arithmetical sign appearing upon the upper side of one of the dice, it indicates that the numbers appearing on the 80 upper side of the other two dice are to be added, subtracted or multiplied, according to the nature of the sign facing upward.

The score pegs 11 are preferably of contrasting color to agree with the colors of the 85 respective game pieces and each peg has a point to enter openings 12 of a game counter, appearing upon the game board. The game counter includes stripes of contrasting color disposed in parallel relation and intersecting the pocket 3, the colors of the stripes corresponding with the colors of the respective game pieces and score pegs. The several stripes are numbered to agree 95 with numbers of the game pieces. The 100 openings 12 are provided in the bottom of the pocket 3 to receive the points of the pegs 11 and hold them in upright position when starting the game. The starting line 9 has openings to receive the points of the game 105 pieces, which are placed in position preliminary to starting the play. In playing the 110

game the dice are cast in the usual way and the points indicated by the upper faces of the dice represent the number of moves of the game piece. When any player occupies either one of the single tracks 6 no other player may advance and after a player clears the single track 6 at either end of the race course, he may advance along any of the tracks which are not occupied and after a player has completed a circuit a lap is registered and the one completing a prescribed number of laps wins and the points may be scored by advancing the proper peg 11 along the proper score line. When the game is not in use the pegs 11, game pieces 8 and play indicators 10 are distributed in the pockets 2 and 3 and said pockets are closed by folding the sections of the game board one upon the other, as will be readily appreciated.

Having thus described the invention, I claim:

1. Game indicating means consisting of dice, certain dice bearing the characters 0 to 5 inclusive on their respective sides and another one of the dice bearing arithmetical

signs, a numeral and a character to designate that the play is backward.

2. A game comprising a base including similar hinged sections having an elliptical race course delineated thereon and comprising a plurality of tracks which gradually and symmetrically merge into single tracks at opposite ends in line with the major axis, there being a starting line at one side coinciding with the minor axis, one of the sections having recesses forming pockets within the course, stripes of contrasting color intersecting one of the pockets and having the portions at one side of the pocket numbered, game pieces of contrasting color and numbered to agree with the said stripes, score pegs of contrasting color to match the stripes and game pieces and dice, certain dice bearing numbers on their faces and another dice bearing arithmetical signs, a numeral and a character to indicate that the play is backward.

In testimony whereof I affix my signature.

JOHN B. SOUSA. [L. s.]
